UNITED STATES PATENT OFFICE.

DANIEL BATEMAN, OF LOW MOOR, NEAR BRADFORD, YORKSHIRE, ENGLAND.

APPARATUS FOR HARDENING AND TEMPERING WIRE.

SPECIFICATION forming part of Letters Patent No. 224,127, dated February 3, 1880.

Application filed November 21, 1879.

To all whom it may concern:

Be it known that I, DANIEL BATEMAN, of Low Moor, near Bradford, Yorkshire, England, have invented a new and useful Improvement in Apparatus for Hardening and Tempering Steel Wire, of which the following is a specification.

My invention relates to certain improvements in apparatus for hardening and tempering steel wire, more especially such as is intended to be used in the making of card-teeth; and my invention consists in certain improvements in the construction of the heating-box, the tempering-bath, and annealing-furnace, as more fully described hereinafter.

In the accompanying drawings, Figure 1 is a vertical section of my improved tempering apparatus; Fig. 2, a sectional plan; Fig. 3, a transverse section on the line 1 2; and Figs. 4 and 5, detached views, referred to hereinafter, of different parts of the apparatus.

A is a box, of fire-clay or other refractory material, the cover of this box consisting of detachable slabs *a*, of the same material. A pipe, B, with open ends, extends lengthwise entirely through this box, and below this pipe is a perforated tube, D, the opposite ends of which pass through one of the side walls of the box, each end of the tube communicating through a branch, *b*, with a gas-pipe, and through a branch, *d*, with an air-pipe, in which air at a pressure of about four pounds per square inch is maintained. Each of these branches is furnished with a suitable cock, so as to properly regulate the supply of air and gas to the tube D.

The box A has a longitudinal slot, or is perforated at the bottom, or it may be furnished with a suitable grate.

Near one end of the box A, and in line therewith, is a trough, E, lengthwise through which passes a tube, F, which, when the apparatus is in operation, is immersed in water, a supply of the latter being maintained in the trough by an inlet-pipe, *e*, and outlet-pipe *f*, so arranged that while a proper depth of water is maintained within the trough fresh water shall continuously flow through the same.

Below the trough E is a reservoir, G, for receiving oil, which, by means of any suitable pumping device, is forced up into an elevated

reservoir, and passes thence through the pipe *h* into the tube F, from which the oil is permitted to flow through an outlet-pipe, *i*, into the reservoir below. The outlet branch is extended upward from the tube a short distance before it is turned down toward the trough, so that while the oil flows freely through the said tube the latter will always be full of oil.

On each end of the tube F a flange or plate, *m*, is secured to the trough E, and in each flange is a dovetailed recess, *n*, for receiving the gate *p*, by which the upper half of the end of the pipe is closed, the lower half being closed by the flange *m*. The under edge of the gate *p* has as many notches as there are wires to be tempered, so that while the wires can pass freely through the tube F the gate *p* will prevent the escape of much oil from the tube. Whatever oil does escape, however, will flow into the reservoir G below.

Near the end of the water-trough E, and in line therewith, is a box, H, of fire-clay or other refractory material, the box being covered by a metal plate, I, beneath which is a perforated tube, J, the latter communicating at one end with the air and gas pipes *t* and *w*, each of which is furnished with a suitable cock.

The box A is, in the first instance, filled with granulated coke or cinders, so that both the pipe B and tube D shall be embedded therein, both gas and air being then introduced into the tube D, and the gas being ignited where it passes through the perforations of the said tube. After the granulated coke has become red-hot the gas may be cut off, the introduction of air, however, into the tube being continued. It has been found that by this plan a uniform temperature can be maintained within the box for many hours without further expense of gas than that first required for a proper ignition of the granulated coke.

It may be advisable to add small supplies of granulated coke to that in the box from time to time, which can be done after removing one or more of the covering-slabs, the spent cinders falling through the openings in the bottom of the box.

The wires *x*, arranged side by side, pass through the pipe B, where they are heated to a bright-red heat, in which condition they pass into and through the oil contained in the pipe

F, the wires thus hardened finally passing from the pipe over and in contact with the plate I, the heat of which and the speed at which the wires pass are so regulated that the 5 desired temper, indicated by the color of the wires, will be imparted thereto.

I claim as my invention—

1. In a wire-tempering apparatus, the combination of a box, A, and a longitudinal pipe, 10 B, surrounded with coke or cinders in said box, with a perforated tube, D, below said pipe, and having air and gas supply branches, all substantially as set forth.

2. The combination of the water-trough E,

having inlet and outlet pipes, the oil-tube F, 15 having an inlet, h, and an outlet-pipe, i, and a reservoir, G, substantially as described.

3. The combination of the oil-tube F and plate m, having a recess, n, with the sliding gate p, provided with notches in its lower edge, 20 as and for the purpose described.

In testimony whereof I have signed my name to this specification in the presence of two subscribing witnesses.

DANIEL BATEMAN.
